United States Patent Office.

EDWARD HOWELL, OF ASHTABULA, OHIO.

Letters Patent No. 68,199, dated August 27, 1867.

IMPROVEMENT IN CARRIAGE-CURTAIN BUTTON.

The Schedule referred to in these Letters Patent and making part of the same.

TO ALL WHOM IT MAY CONCERN:

Be it known that I, EDWARD HOWELL, of Ashtabula, in the county of Ashtabula, and State of Ohio, have invented certain new and useful Improvements in Carriage-Curtain Buttons; and I do hereby declare that the following is a full and complete description of the same, reference being had to the accompanying drawing, making part of this specification, in which—

Figure 1 is a front view of the button.

Figure 2 is a vertical section of the same.

Like letters refer to like parts in the different views.

A, fig. 1, represents the carriage-curtain. B is the button, which consists of two plates attached to the curtain, plate C being placed on the back side and D on the front, a point, b, extending through at each end of the plate D and overlapping the plate C, as shown in fig. 2, thus fastening it securely to the curtain. From the front plate D project the ears a, of the shape shown in fig. 2. To these ears, at d, is pivoted the thumb-piece E, of the shape shown in the drawing. At the end of this thumb-piece is a cam, e, for a purpose hereafter shown. At the top of the front plate D is a rib, e, fig. 2.

The manner of fastening this curtain is as follows: The thumb-piece E is raised, as shown by the dotted lines in fig. 2, and the curtain placed between the ears and the front plate D; the thumb-piece is then brought down, which presses the cam against the rib e, thus holding the curtain securely.

This button can be fastened to the body of the carriage, if desired, or two curtains can be fastened together, if desired.

What I claim as my improvement, and desire to secure by Letters Patent, is—

The cam e and thumb-piece E, pivoted to the cam, and arranged in relation to the rib d and curtain, substantially as and for the purpose set forth.

EDW'D HOWELL.
